MEANS FOR LOCKING CONTAINERS,
CONDUITS, AND THE LIKE

Edith Maud Huime, Brighton, England

Application December 5, 1935, Serial No. 52,989
In Great Britain December 13, 1934

4 Claims. (Cl. 215—98)

My present invention relates to improved means for locking containers, conduits and the like. The invention can be adopted with closure caps for bottles, petrol tanks and other receptacles where it is desirable to safeguard against pilfering or risk of mistake in use, e. g. bottles containing poison and drugs. Likewise the invention is also useful in the locking of petrol taps and valves and other like devices as a safeguard against theft of a motor vehicle and pilfering petrol. The object of my invention is to provide a strong and simple form of lock for use with closure devices in which there are few parts to get out of order or to become distorted or broken.

In carrying one form of my invention into practice with a device suitable for use with a bottle or petrol tank or the like I provide a metal cap of cylindrical form shaped to fit over the neck of a bottle and preferably circumferentially shaped to provide a quick pitch thread to enable it to be threaded into or about the bottle neck. Rotatably disposed about this cap is a relatively loose cover member in the form of a cylinder having an inwardly turned annular ledge at its base to prevent it from being pulled off the cap. For a bottle closure device the cover member preferably has a half spherical upper part so that a neat, half dome shaped cover member is provided, which will not detract from the appearance of the bottle. However, for a petrol tank cap the configuration of the cover member may take the conventional shape to avoid detracting from the normal appearance of the vehicle equipment. The cover member is formed with an internal ledge or has a suitable number of grub screws or pins extending horizontally therefrom to form abutments against the top of the cap so as to prevent the cover member from being pulled off the cap. In the space between the flat upper side of the cap and the top of the cover member is provided the locking means for selectively connecting the cover member to the cap to enable both to be rotated as a single unit. A preferred locking means is a key in the form of a cylindrical pin the free end of which is formed with a short eccentric projection, the cover member and cap being shaped to receive the pin and projection respectively.

In order that my invention may be clearly understood and readily carried into effect I have appended hereto two sheets of drawings illustrating embodiments thereof and wherein:

Fig. 1 is a sectional elevation showing the closure device together with a bottle to which it is fitted.

Fig. 1a shows an adaptor for use with the

closure device shown in Fig. 1 and intended to be fitted onto the necks of bottles which are not threaded.

Fig. 2 is a section on the line 1—1 of Fig. 1.

Fig. 3 is a sectional elevation showing the invention applied to a screw-on cap suitable for use on petrol tanks and the like.

Fig. 4 is a plan view of Fig. 3.

Fig. 5 is a sectional elevation showing the invention applied to a screw-in plug suitable for use on petrol tanks, beer barrels and the like.

Fig. 6 is a section of the line 5—5 of Fig. 5.

Fig. 7 is an end view of the key.

Fig. 8 is a sectional elevation showing the invention applied to a known form of closure cap at present adopted on petrol tanks.

Fig. 9 is a section on the line 8—8 of Fig. 8.

Fig. 10 is an inverted plan view of Fig. 8, and

Fig. 11 is a part sectional elevation showing the invention applied to a petrol tap or the like.

Referring to the drawings, the device illustrated comprises a cap 10 of cylindrical form and a cover member 11 rotatably disposed about said cap and having fixed to it a half spherical head 12 to provide a neat external configuration to the device.

The cap 10 is adapted to be threaded on to the threaded neck of the bottle, but when a bottle not provided with a threaded neck is to be fitted with the closure device an adaptor cap 13 such as shown in Fig. 1a can be tightly gripped about the top of the neck of the bottle to provide the equivalent of the threads 14 shown on the bottle neck in Fig. 1. This adaptor cap is preferably made of vulcanized rubber and is corrugated internally as shown in the drawings and formed with an external circumferential thread to correspond with the internal threading of the cap 10. The internal corrugations can correspond with the convolutions of the external thread of the adaptor cap or may be arranged as a succession of circular channels. Any other suitable method of treating the interior of the adaptor cap may be provided for tightly gripping it about the neck of a bottle.

When the bottle or other container to which the device is to be fitted is of such a nature that it will be retained for a considerable period, e. g. a refillable bottle, the interior of the adaptor cap 13 may be treated with a suitable adhesive agent to permanently secure it to the neck of the bottle.

If desired, the adaptor cap 13 may be made of a malleable metal or alloy which will enable it to be pressed downwardly over the neck of the

bottle. However, it may be made of bakelite or the like and if desired the members 10, 11 and 12 may be made of like material.

The purpose of the cover member 11 is to prevent access to the cap 10, and the arrangement is such that the bottle is locked against use by allowing the member 11 to rotate freely about the member 10 so that rotation of the device will not unscrew it from the bottle or other container. When it is required to unscrew the device from the container the member 11 is relatively immovably coupled to the member 10 by a key.

The method shown of readily connecting the members 10 and 11 against relative rotation comprises a key 15 in the form of a cylindrical pin adapted to be fitted as a smooth but easy fit into an axial cylindrical bore 16 in the upper member 12 of the cover member 11. The member 12 is relatively fixedly secured to the member 11 by grub screws 17 or other suitable fixing means and the top of the cap member 10 is formed with an eccentric recess 18 which registers with the bore 16 but is eccentric in relation thereto. It is preferred to form the bore 16 and eccentric recess 18 in hard metal bushes when the parts 10 and 12 are made of bakelite and other non-metallic material.

It will be apparent that if the key 15 is formed with a depending integral eccentric projection such as 15a adapted to enter the recess 18 a very slight rotation of the key in one direction will frictionally grip the cover member 11 to the cap 10, the key also serving as a means to relatively fixedly couple the members 10 and 11, whereupon the cover member 11 can be rotated so as to carry with it the cap 10. This projection and the recess may of course be modified in size and relative eccentricity, and also the bore 16 can accommodate one or more barrels apertured to receive a key shaped to pass therethrough and enter the recess 18. For example, the body part 15b of the key can have any desired number of grooves, flats or ribs to slide along a correspondingly shaped hole or holes in the barrel or barrels rotatable in the cylindrical recess 16.

The key is retained in the device during rotation of the closure member when applying or when removing the device, but when it is required to close the bottle against use the key is removed and rotation of the member 11 will be idle about the member 10.

The member 11 is inwardly flanged or spun at its lower edge to form an annular ledge 11a adapted to abut against the lower edge of the cap 10 to prevent removal of the cover member 11.

The grub screws 17 can be obscured by plating the device after the grub screws are fitted in position or by coating the device with a suitable colouring agent. The grub screws 17 can be secured against removal by polishing their outer ends flush with the periphery of the member 11.

A suitable washer or sealing member 19 is fitted inside the member 1 to engage the rim of the neck of the bottle or the rim of the member 4.

In order to maintain the concentricity and to provide easy bearing surfaces for the members 10 and 12 the member 10 is formed with a concentric boss 10a and the member 12 is correspondingly recessed to receive such boss.

The foregoing features of construction are adopted in the embodiments shown in Figs. 3 to 10 inclusive with slight modification in configuration and also in the means for securing the

inner cap member 10 to the neck or other part of the appropriate container. In Figs. 3 and 4 the cap element 10 and the relatively rotatable cover constituted by the parts 11 and 12 are made shallower in relation to their diameter than in the arrangement shown in Fig. 1 in order to make the device suitable for use with a petrol tank or the like having a cylindrical externally threaded neck 20. In this embodiment and in those shown in Figs. 5 and 8 the inner cap member 10 is shaped to replace the existing closure cap provided on petrol tanks or the like.

In Fig. 3 the cap member 10 is threaded internally and in Fig. 5 externally, the latter embodiment incorporating a flange 10b on the member 10 to abut against the rim of the neck 20 and to provide the requisite annular seating for the inturned ledge 11a of the cover member 11.

In the embodiment shown in Figs. 8, 9 and 10 a closure device suitable for use with petrol tanks is shown in which is adapted a lock according to one form of my invention. The closure device embodies the known use of a pair of diametrically opposed pair of resilient arms 21 with downturned legs 22 at opposite sides adapted to trip under a pair of fixed pins 24, and upturned bowed ears 23 at the remaining sides adapted to receive such pins as shown in Fig. 1, the said pins being fixed in the neck 20 of the petrol tank. The pairs of arms 21 are formed from a single piece of sheet metal which is secured by rivets 25 to a cupped disc 26 in known manner, but instead of the disc being fixed directly to the cover cap adapted to be held in the hand as is at present the practice it is fixed to the cap member 10 over which is rotatably fitted the cover member 11. Purely by way of example this cover member is shown in this embodiment as made integral with the part 12 and also as having an inwardly spun lower edge forming the ledge 11a. The part 11 is formed with a milled outer surface to facilitate manipulation.

It is apparent from the embodiment shown in Fig. 11 that the invention may be applied to a number of purposes where it is required to prevent pilfering, because by quite simple adaptation a petrol tap or the like 27 can have its plug 28 protected against rotation so that on a motor vehicle or other suitable appliance the supply of petrol or other liquid can be maintained cut off pending access to the key 15. A suitable method of adopting such procedure is to form the plug 28 as an integral or permanently affixed part of a flange like member 10b, being the equivalent of the hereinbefore described member 10. The wings 29 for rotating the plug are formed on the member 12 to which is affixed the cover member 11. To reduce the thickness of the member 12 the member 10b can be concentrically recessed as at 10c instead of being bossed as at 10a aforesaid, and the member 12 is formed with a concentrically bossed part as at 12a to fit in the recess 10c. A cap 30 can be fitted over the usual nut 31 of the plug 28 to prevent rotation of the plug by means of a tool engaged with the nut 31.

The relative eccentric positions of the parts 15a and 15b of the key 15 provide a highly positive coupling between the parts 10 and 11 and there is little risk of fracture or distortion of the key and the parts it engages.

What I claim is:—

1. A closure device for bottles, petrol tanks and other containers comprising a closure member, a cap encircling the aforementioned closure member and rotatable relatively thereto, a key with a

cylindrical part and with an eccentrically related extremity for operatively connecting the cap to the closure member to enable the closure member and cap to be rotated in unison, a circular hole in said cap to receive the cylindrical part of the key, and a key engaging part in said closure member shaped and adapted to fit the said extremity of the key, the said hole and part being eccentrically related and in conjunction 10 with the said key being so shaped that when the key is fitted in said hole and to said part a partial rotation applied to the key effects by reason of said eccentric relationship of the keyhole and said part a seizing or binding couple between the 15 cap and closure member so that they can rotate as one.

2. A closure device for bottles, petrol tanks and other containers comprising a closure member adapted to be engaged with the neck or other 20 convenient part of the receptacle to be closed, a cap encircling the aforementioned closure member and rotatable relatively thereto, a key of circular section, an eccentric projection at one end of said key, said key being adapted to operatively 25 connect the cap to the closure member to enable the closure member and cap to be rotated in unison, an eccentric circular recess formed in the closure member and a circular hole formed in the cap, the said hole and recess being shaped to 30 receive and fit the circular section and eccentric parts of the key whereby upon the key being slightly turned in said eccentric circular hole or recess, the said cap and closure member are slightly rotated relatively to each other so as to 35 cause the cap to bind upon the closure member and so enable the cap and closure member to be rotated as one to unscrew or remove the closure member.

3. A closure device for bottles, petrol tanks and other containers comprising a closure mem-

ber, a cap encircling the aforementioned closure member and rotatable relatively thereto, a key with a cylindrical part and with an eccentrically related extremity for operatively connecting the cap to the closure member to enable the closure 5 member and cap to be rotated in unison, a circular hole in said cap to receive the cylindrical part of the key, and a key engaging part in said closure member shaped and adapted to fit the 10 said extremity of the key, the said hole and part being eccentrically related and in conjunction with the said key being so shaped that when the key is fitted in said hole and to said part a partial rotation applied to the key effects by reason of said eccentric relationship of the keyhole and 15 said part a seizing or binding couple between the cap and closure member so that they can rotate as one, a concentric cylindrical boss and a concentric cylindrical recess being provided in opposed faces of said cap and closure member fitting 20 snugly one within the other, the said hole and recess being located within the circumference thereof.

4. Lock for rotary taps, valves, plug cocks and the like comprising a cylindrical body for rotat- 25 ing the rotary part of the tap, valve or the like, a cap loosely encircling said body and covering the upper face of said body, a central circular aperture in the top of said cap, a cylindrical key adapted to fit in said aperture, and correspond- 30 ing projection and recess on said key and in said body respectively adapted to fit one within the other and eccentrically related to the axis of said aperture and key, the arrangement being that said cap is adapted to be locked to said body by 35 a partial rotation of said key whereupon said cap and body are coupled to provide an accessible means for rotating the said rotary part of the valve or the like.

EDITH MAUD HULME. 40
